UNITED STATES PATENT OFFICE.

JOHN SCHUMACHER, OF LOS ANGELES, CALIFORNIA.

PLASTER BOARD.

Original application filed November 14, 1921, Serial No. 514,914. Divided and this application filed April 13, 1925. Serial No. 22,583.

To all whom it may concern:

Be it known that I, JOHN SCHUMACHER, a citizen of the United States, and resident of Los Angeles, in the county of Los Angeles and State of California, have invented new and useful Improvements in Plaster Board, of which the following is a specification.

This invention relates to a plaster board 10 formed of a plaster core and covering sheets. Such boards are commonly used for covering walls in building constructions. The present application is a division of application Ser. No. 514,914, filed November 14, 1921.

It is the primary object of this invention to provide a board which is reinforced at the edges, and with the covering sheets so arranged that they are securely attached to 20 the plaster core at their edges, thereby preventing the sheets from being accidentally pulled away from the plaster or torn at the edges in handling. It is another object of this invention to provide a board so reinforced at its edges, that it will not chip. It is a further object of this invention to provide a board of the character described having a full width exposure of the plaster core at the edges, so as to provide for better ad- 30 herence of joint cement.

Other objects and corresponding accomplishments will be apparent from the subjoined specification and drawing accompanying the specification, in which: The 35 figure shows in perspective one type of board embodying my invention.

Referring more particularly to the figure a board is shown comprising a plasterer core 1 disposed between cover sheets 2 and 3. I prefer to use a moist unstable plastic substance, which may be fed between continuously advancing sheets of paper. The side margins of the paper sheets are turned inwardly at acute angles and embedded in the plaster leaving the end faces exposed. 40 The product in its soft condition is cut into initial lengths. In setting and drying, the paper adheres to the plaster core 1. The end faces are in effect completely exposed forming a face permitting an adherence of 50 the joint filler used between sections. The edges of the paper are embedded in the plaster core and form a reinforcement which strengthens the board. There is no opportunity for the board to start peeling at the 55 edge, as the edge of the paper is embedded in the plaster so as to anchor them securely.

What I claim is:

A plaster board comprising a plaster having covering sheets adhering to the outer faces thereof and folded back at an acute angle at the junctions of the side edges and faces of the board so as to cover the corner edges thereof, the extreme ends of the said sheets being folded into and embedded in 60 the plaster so as to expose the plaster at the end faces for the full thickness of the board.

In witness that I claim the foregoing I have hereunto subscribed my name this 6th day of April 1925.

JOHN SCHUMACHER.
